W. C. CURRAN.
SIGN PLATE,
APPLICATION FILED JAN. 17, 1914.

1,127,599.

Patented Feb. 9, 1915.

UNITED STATES PATENT OFFICE.

WILLIAM C. CURRAN, OF CINCINNATI, OHIO.

SIGN-PLATE.

1,127,599.

Specification of Letters Patent.

Patented Feb. 9, 1915.

Application filed January 17, 1914. Serial No. 812,665.

To all whom it may concern:

Be it known that I, WILLIAM C. CURRAN, a citizen of the United States, residing at Cincinnati, in the county of Hamilton and State of Ohio, have invented a new and useful Sign-Plate; and I do hereby declare the following to be a full, clear, and exact description of the invention, such as will enable others skilled in the art to which it appertains to make and use the same.

This invention relates to a new and useful sign plate.

An object of the invention is to provide a sign plate, on which any suitable sign or other lettering may be printed, and provided with underbent flanges having slits or cuts to receive the shanks of tacks or the like, the heads of which engage between said flanges and the body of the sign plate, whereby the plate may be tacked or secured to a stationary support, such as a fence post or paling, or upon the side of a house or the like, the heads of the tacks being obscured from view. Said flanges are also constructed with triangular struck up tangs, which may be used to be driven into the fence post or paling or other suitable support, thereby avoiding the use of tacks, especially upon small sign plates. It will be observed that by striking up these tangs, triangular openings are formed in said flanges, and if desired, the tack heads may be inserted through said openings, and the tangs bent toward the shanks of the tacks, after which the tacks may be driven into the supports.

In practical fields the details of construction may be subjected to alterations falling within the scope of what is claimed.

The invention comprises further features and combination of parts, as hereinafter set forth, shown in the drawings and claimed.

In the drawings:—Figure 1 is a view in perspective showing the sign plate fastened to a fence paling or other support. Fig. 2 is a sectional view on line 2—2 of Fig. 1, not only showing the tacks held in said slits, but also in said triangular opening.

Fig. 3 is a perspective view of the sign plate detached, looking at the rear of the plate, showing the tacks held in said flanges. Fig. 4 is an enlarged detail view of a portion of the plate. Fig. 5 is a plan view of the blank. Fig. 6 is a sectional view on line

6—6 of Fig. 2, showing attaching means in said triangular openings.

Referring more especially to the drawings, 1 designates a sign plate, which may be constructed of any suitable material and any desired shape. In the present instance the same is shown as being constructed of sheet metal, such as tin or the like, and in an oblong contour. The outer portions adjacent the edges of the plate are bent upon themselves as shown at 2 to form the longitudinal and transverse flanges 4. To form these flanges without their ends overlapping, the corners of the blank are slitted or cut as shown at 5 to form the openings 6, then by bending the outer edge portions of the blank upon the scored lines 7, 8, 9 and 10, the flanges will substantially meet as shown at 11. These flanges are provided with slits or cuts 12, to receive the shanks of tacks or the like, the heads 13 of the tacks engaging between the flanges and the body of the plate, thereby obscuring the heads of the tacks from view, when the tacks are driven home. In utilizing the sign plate, any suitable sign, such as shown in the drawing, may be painted, engraved, or otherwise placed upon the front face of the plate, then by blows from a hammer or the like upon the front of the sign just over the tack heads, the tacks may be driven home. The flanges are also constructed with struck up tangs 14, which are triangular, and designed to be driven into the support or the like, in lieu of tacks, in order to attach the sign plate. If desired the heads of the tacks may be inserted in the openings 15, then the triangular tangs bent toward the shanks of the tacks, after which the tacks may be driven into the supports, thereby affording another means for attaching the sign plate as shown in Fig. 6. Both attaching means may be utilized at the same time if desired, that is, in attaching large and heavy sign plates. The tang attaching means may be utilized for securing small sign plates. It will be observed that all classes of advertisement may be printed or otherwise placed upon the plate, and the attaching means are obscured from view.

The invention having been set forth, what is claimed as new and useful is:—

A sign plate to receive advertising matter constructed of sheet metal, flanges extending along the edges of said plate, the plate

being scored at the junction of each flange with the body of the plate, the corners of said flanges being cut away whereby the flanges are adapted to be folded upon the plate without overlapping; said flanges having slots to receive headed attaching means, said flanges being provided with triangular tangs constituting additional attaching means, said flanges having triangu-

lar openings adjacent said tangs to also receive headed attaching means.

In testimony whereof I have signed my name to this specification in the presence of two subscribing witnesses.

WILLIAM C. CURRAN.
